CAR-DOOR-OPERATING MECHANISM.

1,424,814.

Specification of Letters Patent. Patented Aug. 8, 1922.

Application filed October 18, 1919. Serial No. 331,627.

To all whom it may concern:

Be it known that I, ALBERT GOTTSCHALK, a citizen of the United States, and resident of New York, in the county of Bronx and 5 State of New York, have invented a certain new and useful Improvement in Car-Door-Operating Mechanism, of which improvement the following is a specification.

This invention relates to mechanism for 10 operating doors, such as car doors, on trains of one or more cars, particularly adapted for multiple unit train service such as employed on subway and elevated railways, where it is desirable that the doors of one or more cars 15 may be controlled from a single point.

One of the objects of my invention is to provide improved means for controlling the operation of the door motor, whereby the fluid pressure for actuating the motor may 20 be controlled either electrically or pneumatically, or by both agencies, as desired. Another object is to provide means for automatically preventing the opening of any one or more doors that are not opposite the platform at the time when the mechanism is 25 manipulated to open the car doors. With these and other objects in view, my invention comprises certain improved constructions which will now be more fully described, the 30 novel features and combinations being set forth in the claims.

In the accompanying drawings: Figure 1 is a diagram of a car equipment of door operating mechanism embodying my improvement; Fig. 2, a vertical longitudinal section of one form of door operating motor, and a magnet valve device connected thereto; Fig. 3, a transverse section taken on the line 3—3 of Fig. 2; Fig. 4, a diagram, in 40 plan, illustrating one relation of the safety switches of the door circuits to the car platform; Fig. 5, a plan, showing one form of safety switch; and Fig. 6, a view showing a modified form of safety switch.

45 In the class of service above referred to, the cars are provided with a plurality of doors, usually three or more on each side, and there is a fluid pressure motor connected to each door for operating the same.

50 In the diagram, Fig. 1, there are three such door motors, 13, shown, but it will be understood that any desired number may be employed. Any suitable or preferred form of fluid pressure motor may be used for opening and closing the door, and I have illus-

trated, in Fig. 2, a standard form of differential motor comprising a casing having opposite cylinders of different diameters and containing the differential pistons, 14 and 15, connected by rack bar, 16, meshing with segmental gear, 17, mounted on shaft, 18, in the gear case, 19. The shaft also carries an arm, 20, outside the casing, for operating the door in the usual manner. The smaller piston head, 14, may be subject to the fluid 60 pressure at all times, admitted by pipe, 21, from a source of supply, such as reservoir, 22, while a valve, 23, mounted on a seat on the small cylinder head controls the supply of fluid to the opposite cylinder and large 65 piston, 15, through port, 24, and the exhaust therefrom, to operate the motor. When the valve is turned to its position for admitting fluid to passage, 24, and to the large piston, 15, the force overcomes the pressure acting 70 on the small piston, 14, and moves the differential piston to the right, thereby operating through the gear and shaft connection to turn the arm, 20, down to a substantially 75 horizontal position and close the door. 80

According to one of the features of my invention, improved means are provided for shifting the valve, 23, of the motor either electrically or pneumatically. As shown in Figs. 2 and 3 of the drawings, one construction for this purpose comprises a piston, 25, contained in a cylindrical chamber formed in one head of the motor cylinder, and adapted to operate a cam member, 26, mounted on the stem, 27, of the valve, 23. 85 The rotation of the stem 27 rotates the valve 23 to cover or uncover its respective ports in the usual manner, that is, to in any one position establish communication between the source 21 and the port 24 leading into the 90 cylinder of larger diameter behind the piston 15 in the one instance and to exhaust the said pressure in the other instance, as is the usual well established practice with differential 95 motors of this type. The rotary valve is as 100 shown located directly within the cylinder and is carried by, to form part of, the cylinder head, in this instance of the cylinder of smaller diameter. A spring, 28, normally holds the piston, 25, in one position with the 105 valve, 23, in position to supply the fluid to the port, 24, and the large head, 15, of the motor piston, which is the door closing position. In order to shift the valve, 23, to its 110 other position for exhausting fluid from the

- large cylinder to open the door, I provide a standard magnet valve device, 30, the coil of which is connected to the door operating circuit, 31, and having its armature attached to the supply valve, 32, and exhaust valve, 33, in the usual way. The supply valve, 32, is normally held closed by a light spring and the fluid pressure admitted by passage, 34, to the spring chamber beneath the valve, while the exhaust valve, 33, opens communication from the chamber of piston, 25, through passage, 35, to the exhaust port, 36, and the atmosphere. When the magnet coil is energized, however, the exhaust valve, 33, is closed and the supply valve, 32, is opened for admitting fluid pressure from the supply, 21, and port, 34, through passage, 35, to the piston, 25, to shift the valve, 23, to its position for opening the door.
- For operating the valve by a direct control of fluid pressure independently of the magnet valve, an additional piston, 25^a, may be mounted in close proximity to piston, 25, and arranged to co-operate with the same against the action of the spring, 28. The supply of fluid to the piston, 25^a, by means of pipe, 37, may be controlled by a manually operated valve, such as indicated at 38, in Fig. 1, and having a port, 39, adapted, in one position to connect the supply pipe, 21, with pipe, 37, and in another position, to open communication from the pipe, 37, to the exhaust pipe, 40. The contacts, 41, of the door operating circuit, 31, to the magnet valves, 30, are also preferably mounted in close proximity to the valve, 38, so that the movable contact, 42, for closing the circuit across contacts, 41, may be operated by the same handle, 43, of the manual valve.
- When the handle, 43, is in the position shown, the pipe, 37, is exhausted to the atmosphere, and the circuit, 31, is open, so that the spring, 28, acting through piston, 25, moves cam, 26, to the position shown in Figure 2, and thereby rotates the valve stem 27 and turns the valve, 23, to the closed door position i. e. with the cylinder of larger diameter in communication with the source of pressure. When the handle, 43, is turned a short distance, clockwise, the exhaust passage, 40, is cut off, and the contact, 42, closes the circuit, 31, at the points, 41, thereby energizing the magnet valves, 30 to operate all the door motors to the open door position as before described. If, for any reason, the electric operation should fail, a slight further movement of the valve handle, 43, serves to connect the supply pipe, 21, with the pipe, 37, thereby admitting fluid to the piston, 25^a, of all the door motor valve devices and operate the same to open the doors. When the hand valve, 38, is turned back to the closing position, the fluid is exhausted from pipe, 37, through cavity, 39, and pipe, 40, to the atmosphere, and the springs, 28,

return the distribution valve, 23, to the position for actuating the motors to close the doors.

It will be noticed that the port, 35, for supplying fluid from the magnet valve communicates with the space between the pistons, 25 and 25^a, in their normal positions, so that when the magnet valve is energized, the fluid from port, 35, acts on piston, 25, to move the same away from the piston, 25^a, but the latter piston prevents the escape of the fluid into the pipe, 37. This piston also prevents escape of fluid from pipe, 37, to the passage, 35, and the exhaust port of the magnet valve, when the distribution valve is operated pneumatically by a direct supply of fluid by hand valve, 38, to the pipe, 37. It will thus be seen that the two systems are independent, so that when operating with either one, the exhaust from the other is closed and there is no interference in the operation.

While I have shown a standard form of differential piston motor and interior rotary valve for operating the door, it will be understood that my invention is not limited thereto, but is equally applicable to any suitable form of fluid pressure motor and distribution valve therefor.

According to another feature of my improvement, the operating circuits to the respective magnet valves, 30, of the door motors are each provided with an automatic switch device so controlled by the relation of the car to the platform that when any particular car door is not opposite the platform, the switch in the circuit to that particular magnet valve shall be open, so that only the doors that are opposite the platform will be opened when the handle is moved by the operator to the position for energizing the magnets to open the doors. Such a switch is indicated, diagrammatically, at 45, Fig. 1, in the branch circuits to the magnet coils, 30, and is shown more in detail in Figs. 4, 5, and 6. As shown in Fig. 5, the switch comprises an arm, 46, pivoted upon a bracket, 47, and carrying the movable contact member, 48, for opening and closing the circuits, 31, at the fixed contact points, 49. The arm is normally held in its extended position from the side of the car by a spring, 50, with the switch open, but when the arm engages the platform as the car passes along, it swings on its pivot to close the switch, 45, as indicated in dotted lines in Fig. 5. The arms may be located at the doors so that if any one or more of said doors should not be opposite the platform at the time the train stops, such switches will remain open, as indicated at the left in Fig. 4, and the magnet valves of such door motors will not be energized. This is a safety feature for preventing possible danger and accident by falling from an inad-

vertently opened door. Fig. 6 shows a modified form of automatic switch, in which the circuit is closed by a conductor strip, 45^a, mounted on the platform and adapted to engage projecting contact fingers, 45^b, mounted on the car.

Having now described my invention, what I claim as new and desire to secure by Letters Patent is:

10 1. In a door operating mechanism, the combination of a fluid pressure motor for the door, and means for controlling the operation of the motor either electrically or pneumatically.

15 2. In a door operating mechanism, the combination of a fluid pressure motor for the door, electric means for controlling the operation of the motor, and pneumatic means for also controlling the operation of said motor.

20 3. In a door operating mechanism, the combination of a fluid pressure motor for the door, electric means for controlling the operation of the motor, and pneumatic means for also controlling the operation of said motor, and a single handle for controlling both of said means.

25 4. In a door operating mechanism, the combination of a fluid pressure motor for the door, a valve therefor, electric means for controlling the operation of said valve, and a manual valve for also controlling the operation of the said valve.

30 5. In a door operating mechanism, the combination of a fluid pressure motor for the door, a valve therefor, a fluid pressure device for shifting said valve, a magnet valve for controlling the fluid pressure acting on said device, and a manual valve for also controlling said fluid pressure.

35 6. In a door operating mechanism, the combination of a fluid pressure motor for the door, an electric means for controlling the operation of the motor, a switch therefor, a manual valve for also controlling the operation of the motor, and a single handle for the switch and valve.

40 7. In a door operating mechanism, the combination of a fluid pressure motor for the door, an electric means for controlling the operation of the motor, a switch therefor, a manual valve for also controlling the operation of the motor, and a single handle for the switch and valve; and adapted by one movement to close the switch and by another movement to open the valve.

45 8. In a door operating mechanism, the combination of a door motor, a valve for controlling the fluid pressure to operate said motor, a piston device for actuating said valve, a manual valve for controlling a supply of fluid pressure to said piston, and a magnet valve for also admitting fluid to actuate said piston.

50 9. In a door operating mechanism, the

combination of a door motor, a valve for controlling the fluid pressure to operate said motor, a piston device for actuating said valve, a manual valve for controlling a supply of fluid pressure to said piston, a magnet valve for also admitting fluid to actuate said piston, and a single handle for operating the manual valve and for controlling a circuit to said magnet valve.

55 10. In a door operating mechanism, the combination of a door motor, a valve for controlling the fluid pressure to operate said motor, a piston device for actuating said valve, a manual valve for controlling a supply of fluid pressure to said piston, a magnet valve for also admitting fluid to actuate said piston, said magnet having a circuit with switch contacts mounted on the manual valve, and a single handle for operating said valve and switch.

60 11. In a door operating mechanism, the combination of a door motor, a valve for controlling the fluid pressure to operate said motor, a piston for shifting said valve to one position, and a magnet valve device operating when energized to supply fluid to said valve operating piston, and when de-energized to exhaust fluid from said piston.

65 12. In a door operating mechanism, the combination of a door motor, a valve for controlling the fluid pressure to operate said door, a piston device for shifting said valve to one position, a magnet valve device for controlling a supply and release of fluid to and from said piston, and a manually operated valve for also controlling a supply and release of fluid to and from said piston.

70 13. In a car door operating mechanism, the combination with a car door and a motor therefor mounted on the car, of a manually operated device for controlling the door motor, and means governed by the position of the car along the track for also controlling the operation of the door motor.

75 14. In a car door operating mechanism, the combination with a plurality of car doors and motors therefor, of manually operated means for controlling the operation of said motors, and means governed by the relation between the car doors and the platform for also controlling the operation of said motors.

80 15. In a car door operating mechanism, the combination with a plurality of car doors and motors therefor, of manually operated means for controlling the operation of said motors, and means governed by the relation between the car doors and the platform for preventing the opening of such doors as are not opposite the platform.

85 16. In a car door operating mechanism, the combination with a plurality of car doors and motors therefor, of manually operated means for controlling the operation of said motors from a single point, and

means governed by the position of the respective car doors relative to the platform along the track for controlling the operation of said motors independently of each other.

17. In a car door operating mechanism, the combination with a plurality of car doors, and motors therefor, of electric circuits and a manually operated switch for controlling the operation of said motors, and switches located in the circuits to the respective door motors, said switches being governed by the position of the respective car doors relative to the platform along the track.

18. In a car door operating mechanism, the combination with a door and a motor therefor, of means for controlling the operation of said door motor, and a device inserted in the control connection to said door motor for interrupting its operation and governed by the relation between the car and the platform along the track.

19. In a car door mechanism, the combination with a plurality of car doors and 25 motors therefor, of electric means for controlling the operation of said door motors from a single point, switches located in the circuits to the respective door motors, and devices governed by the relation between the 30 car and platform for opening and closing said switches.

20. In a car door mechanism, the combination with a plurality of car doors and 35 motors therefor, of electric means for controlling the operation of said door motors from a single point, switches located in the circuits to the respective door motors, pivoted arms mounted on the car and adapted to engage an object along the track for operating said switches, and means normally holding said arms in an extended position.

In testimony whereof I have hereunto set my hand.

ALBERT GOTTSCHALK.
